UNITED STATES PATENT OFFICE.

FRANCISZEK REMBECKI, OF TROY, NEW YORK.

TORPEDO-DEFLECTOR.

1,289,264.

Specification of Letters Patent. Patented Dec. 31, 1918.

Application filed September 9, 1918. Serial No. 253,220.

To all whom it may concern:

Be it known that I, FRANCISZEK REMBECKI, a citizen of Russia, residing at Troy, in the county of Rensselaer and State of 5 New York, have invented certain new and useful Improvements in Torpedo-Deflectors, of which the following is a specification.

The primary object of the invention is the provision of a protector for ships in the nature of a deflector whereby any torpedoes or similar missiles traveling toward the ship will be changed in their course and prevented from striking the ship.

A further object of the invention is the provision of means carried by the hull of a ship for stopping an oncoming torpedo in such a manner as to prevent an explosion from occurring too near the hull, thereby saving the ship and leaving the same uninjured.

With these general objects in view, the device consists of the novel combination and arrangement of parts hereinafter fully described in connection with the accompanying drawings setting forth the invention, and in which like reference characters designate corresponding parts throughout the several views.

In the drawings,

30 Figure 1 is a top plan view of a ship provided with the invention;

Fig. 2 is an end view thereof partially broken away;

Fig. 3 is an enlarged vertical transverse 35 sectional view of a portion of the same illustrating one member of the invention by dotted lines in its inoperative position;

Fig. 4 is an enlarged side elevation of one 40 of the torpedo-engaging members;

Fig. 5 is a top plan view thereof illustrating a portion of a torpedo by dotted lines;

Fig. 6 is an elevational view of the same 45 partially broken away taken at a different angle from the point of view of Fig. 4; and

Fig. 7 is a top plan view thereof with a torpedo illustrated by dotted lines in its engaged position.

My invention is illustrated in connection 50 with the hull 10 of a ship and consists of a plurality of frames 11 outwardly projecting from the opposite sides thereof downwardly inclined, each of said frames having a torpedo-deflecting spider 12 journaled at its free end.

A bracket 13 is hinged as at 14 to each frame 11 having a shaft 15 journaled in its outer end as at 16 while one of the spiders 12 is secured upon the lower end of each of said shafts 15.

60 A pinion 17 carried by each shaft 15 is adapted for turning by means of a pinion 18 mounted upon a shaft 19 journaled upon the adjacent bracket 13 and operatively connected with a shaft 20 journaled upon its 65 respective frame 11.

Operating means such as a sprocket-chain 21 are provided within the hull 10 for turning the shafts 20 whereby the shafts 15 and spiders 12 are operatively revolved in the direction indicated by the arrows in Fig. 1 of the drawings, it being understood that the rounded end of the hull 10 is the forward or bow end thereof while the pointed end is the stern.

70 A cord 22 is provided for elevating the brackets 13 being attached to the brackets at points 23 and passing through openings 24 in the sides of the hull 10 for winding upon drums 25 journaled within the hull. Upon 75 winding up the cords 22, the brackets 13 are elevated positioning the shafts 15 and spiders 12 out of the water, as illustrated by dotted lines in Fig. 3 of the drawings. A spring 26 is connected between each frame 80 11 and the bracket 13 hinged thereto. It will be understood that upon elevating the brackets 13 by means of the cords 22, the operative connections between the adjacent 85 ends of the shafts 19 and 20 will be broken 90 while upon releasing the said cords, the spiders as well as the brackets 13 descend to their operative positions and at which times the shafts 19 and 20 are operatively connected.

95 The spiders 12 are the members actively affecting an oncoming missile such as the torpedo 27 illustrated by dotted lines in Figs. 5 and 7 of the drawings, each spider having four radial arms 28 with hands 29 at their outer free ends in the form of arcuate disks having slightly less circumferential dimensions than a circle.

100 A substantially semi-circular rack 30 is slidably mounted upon each hand 29 having a cross-head 31 at its free end outwardly of the straight side 32 of the carrying hand, the said head being adapted to engage an oncoming missile. The rack 30 is journaled upon the hand 29 by means of a pin 33 passing through a strip 34 carried by the rack. 110

A plurality of return springs 35 for the rack 30 are attached to the pin 33 while a turn-post 36 is connected to the rack by means of a cord 37 in such a manner that upon revolving the post 36 the rack 30 will be slidably swung upon the hand 29 bringing its head 31 substantially in contact with the edge 32 thereof.

A hook 38 is pivoted beneath the hand 29 at 39 and projects through an opening 40 for engaging rearwardly of a lug 41 upon the rack 30 to retain the rack in its set position with the springs 35 under tension. A trip lever 42 is pivoted to the hand as at 43 being also pivoted as at 44 to the hook 38 while the free end of the trip normally projects above the hand 29 through an opening 45 provided therein.

A substantially cycle-shaped hook 46 has its handle 47 hinged as at 48 to the inner end of the rack 30, the handle being in arcuate alinement with the rack when the handle is depressed and at which times, the trip 45 is engaged by the handle 47 retaining the hook 38 out of engagement with the rack lug 41.

A curved bar 49 is pivoted as at 50 upon the hand 29 extending downwardly through a slot 51 in the hand for engagement by the socket portion 52 of a pusher 53 carried by the rack 30 and also extending through the slot 51 of the hand. A foot 54 is carried by the bar 49 engaging beneath the handle 47 when the handle is depressed and whereby upon revolving the rack 30 to its set position, the pusher 53 will operate the bar 49 to elevate the foot 54, causing the hook 46 to swing upon its hinge 48 to its elevated set position.

A retainer 55 is carried by the handle 47 adapted for manual engagement with the angular end 56 of a rod 57 slidably mounted through a post 58 secured to the hand 29. A guard 59 is resiliently mounted outwardly of the post 58 by means of rods 60 having encircling springs 61 thereon positioned between the post 58 and the guard 59. The rod 57 is also attached to the guard 59 and has a cushioning spring 62 thereon at a point between the post 58 and guard 59.

A spring 63 is carried by the hand 29 connected to a loop 64 upon the handle 47 normally tending to lower the handle upon the hand 29. The operation of the device will be apparent from this detailed description thereof, the manner of elevating and lowering the spiders having been previously set forth.

When the hook 46 is in its lowered position with the rack head 31 and the guard 59 in their outermost positions, the post 36 is turned for revolving the rack 30 against the springs 35, thereby setting the rack with the hook 38 engaged beneath the lug 41 thereof and with the head 31 substantially

engaging the side 32 of the hand. This movement of the rack 30 causes the pusher 53 to operate the bar 49 and elevate the hook 46, and whereupon the retainer 55 is connected to the rod end 56, retaining the hook elevated against the action of its spring 63. It will be evident that when a missile or any other object engages the guard 59 forcing the same inwardly toward the hand 29, the rod 57 will be moved inwardly, releasing the same from the retainer 55. The hook 46 is then drawn downwardly by the spring 63 and the handle 47 engaging the trip 42 depresses the hook 38, releasing the rack 30. The said rack will swing around in the direction indicated by the arrow in Fig. 7 for engaging its head 31 with the missile 37 while the quick operation of the entire mechanism permits the hook 46 to overlie the missile 27.

All of these operations when taken with the revolving of the spider 12 resiliently engage the missile and are designed to deflect the missile without stopping the same. The deflecting of the torpedo is calculated to be such as to prevent its onward course of travel from injuring the hull 10. The continued course of the missile 27 will be away from the ship in the general direction of the attacking vessel.

It will be understood that any object of which the invention is capable such as stopping any form of missiles and changing the course of travel lies within the spirit and scope of my invention as set forth in the accompanying claims. It will be understood that the revolving spiders 12 at each side of the ship are only slightly spaced apart so that the revolving of the spiders prevents missiles from passing the row of spiders so as to injure the hull. The spiders 12 may be positioned wherever desired with respect to the surface of the water but are preferably slightly beneath the surface at a level usually traveled by torpedoes and the spiders are also preferably at points sufficiently removed from the hull so that the explosion of a torpedo, if it should occur, would not injure the ship. The spiders in this manner act as protectors for the hull, either resiliently stopping or deflecting the course of travel of oncoming missiles.

What I claim as new is:—

1. In combination with a hull, hinged supporting members normally outstretched from the opposite sides thereof, means operable inwardly of the hull for elevating the support to its inoperative position, shafts depending from the outer free ends of the supports and journaled therein, revolving means for said shafts operable within the hull, deflecting spiders upon the free ends of said shafts, hands at the outer ends of the arms of said spiders, missile-engaging means resiliently carried at one side of said

hands, a head shiftably carried by each of said hands, and a missile-engaging hook hingedly connected to each head.

2. In combination with a hull, hinged 5 supporting members normally outstretched from the opposite sides thereof, means operable inwardly of the hull for elevating the support to its inoperative position, shafts depending from the outer free ends of the 10 supports and journaled therein, revolving means for said shafts operable within the hull, deflecting spiders upon the free ends of said shafts, hands at the outer ends of the arms of said spiders, missile-engaging 15 means resiliently carried at one side of said hands, a head shiftably carried by each of said hands, a missile-engaging hook hingedly connected to each head, means for normally holding the hook elevated, means 20 for normally holding said heads retracted, and means adapted for the automatic release of said hook upon the engagement of a missile with said engaging means whereby said head is automatically moved toward the missile 25 simultaneously with the positioning of the hook overlying the same.

3. In combination with a hull, a spider revolvably mounted outwardly thereof, arms upon said spider, hands at the outer ends of 30 said arms, an arcuate rack slidably positioned upon the hand, a missile-engaging

upright head carried by one end of the rack, resilient positioning means for the rack, retracting means for the rack, retaining means for the rack when retracted, and a missile-engaging hook hinged to the rack adapted 35 when operated for releasing the rack for substantially simultaneous movement of the head.

4. In combination with a hull, a spider 40 revolvably mounted outwardly thereof, arms upon said spider, hands at the outer ends of said arms, an arcuate rack slidably positioned upon the hand, a missile-engaging upright head carried by one end of the rack, 45 resilient positioning means for the rack, retracting means for the rack, retaining means for the rack when retracted, a missile-engaging hook hinged to the rack adapted when operated for releasing the rack for 50 substantially simultaneous movement of the head, a missile engaging member carried by the hand, resilient connections between said engaging member and hand, and means carried by said engaging member adapted for 55 tripping engagement with the said hook whereby the hook is normally maintained in its set position for automatic releasing upon the engagement of the engaging means by a missile. 60

In testimony whereof I affix my signature.
FRANCISZEK REMBECKI.
